UNITED STATES PATENT OFFICE.

FRANK L. GILMAN AND WILLIS M. BAUM, OF LOS ANGELES, CALIFORNIA; SAID
GILMAN ASSIGNOR TO SAID BAUM.

UNDERWATER-MINING MACHINE.

1,321,302.

Specification of Letters Patent.

Patented Nov. 11, 1919.

Application filed February 25, 1918. Serial No. 219,043.

To all whom it may concern:

Be it known that we, FRANK L. GILMAN and WILLIS M. BAUM, both citizens of the United States, and residents of Los Angeles, 5 in the county of Los Angeles and State of California, have invented certain new and useful Improvements in Underwater-Mining Machines, of which the following is a specification.

10 Our invention relates to mechanism for use for mining purposes in river beds, under swift flowing water, and the recovery of valuables from sunken wrecks and the object thereof is to provide mechanism of this 15 character which will be simple in construction and efficient in operation, and which can be easily and quickly transported from place to place as required.

Another object is to provide a device for 20 the above purpose which is adapted for location and operation at any desired place of use.

A further object is to provide mechanism 25 of the character described which is adapted for use in varying depths of water without alteration and which will be entirely self-contained in that all operative parts and the like will be carried by the same.

Other objects and advantages will appear 30 hereinafter and while we have shown and will describe our preferred form of our invention, it will be understood that we do not limit ourselves to such preferred form but that various changes may be made both in 35 the form and mode of operation, or either of them, without departing from the spirit of our invention.

We accomplish the above and other objects by the mechanism described herein 40 and illustrated in the accompanying drawings forming a part hereof in which.

Figure 1 is a top plan of our invention complete ready for use.

Fig. 2 is a side elevation of Fig. 1.

45 Fig. 3 is an end elevation of Fig. 2, on an enlarged scale.

Fig. 4 is a central longitudinal section of Fig. 1, on an enlarged scale.

50 Fig. 5 is an enlarged detail of the gate operating means.

Fig. 6 is an enlarged detail of one of our buckets.

Figs. 7 and 8 are enlarged details of our grappling device for lifting the buckets 55 from the chutes.

Figs. 9, 10, and 11 are enlarged details of operative parts of our machine.

In the drawings our invention comprises two barges 5 mounted parallel to each other but spaced apart the required distance and 60 are tied together by floor boards 6 or other means a rectangular opening 7 being left centrally of the flooring. This flooring provides a platform 8 upon which the operating mechanism of the device is mounted. 65 Extending upwardly from near each corner of the rectangular opening 7 are pillars or standards 9, 10, 11 and 12, upon the upper end of which are mounted longitudinal cross pieces 13 and 14 and transverse cross 70 pieces 15 and 16. Secured to the sides of barges 5 a short distance from each end of the rectangular opening 7 are spaced pairs of vertically extending L-shaped guide rails 75 17. Mounted within the rectangular opening 7 is a rectangular diving bell 18 which is of a size somewhat smaller than the rectangular opening 7 and is adapted to pass vertically therethrough. Near each end of the diving bell are rigidly mounted vertically extending guide rails 19, T-shaped in cross section, the outwardly projecting flanges of which are positioned between the opposed flanges of each pair of rails 17 80 which form a guide way to confine the diving bell to a vertical path of movement. Mounted on platform 8 at one end thereof is a gasoline engine or other motive force 20 which is connected by a belt 21 to a pulley 22 on shaft 23. Shaft 23 is mounted in bearings 24 and 25 extending upwardly from platform 8. An air compressor 26 is driven by a belt 27 and pulley 28 on shaft 23, and a storage tank 29 receives a supply of compressed air from the compressor. The diving bell 18 is divided intermediate its vertical length by a partition 30 which is air tight into a water compartment 31 and a working chamber 32, it being understood 90 that the ends of these chambers 31 and 32 are open except that a latticed covering 33 is provided for the top of the water chamber. Extending upwardly from partition 30 on the longitudinal center thereof and equally spaced apart are two rectangular 95 working chutes 34 and 35 which extend upwardly from said partition to a short distance above the top of water chamber 31 and are open at their upper ends, a flange 36 being mounted thereon for a purpose here- 100 110

after explained. Chutes 34 and 35 extend downwardly from partition 30 to a short distance above the bottom of working chamber 32 and are closed at their lower 5 ends. A door 37 is provided in the walls of chutes 34 and 35 to allow access to the interior of the chutes, suitable provision being made for rendering the doors airtight when the same are closed. Each of chutes 10 34 and 35 have provided in one wall immediately below partition 30, an enlarged portion 38 in which is mounted a door 39. A handle 40 provides means for operating said doors as hereafter explained, suitable 15 means being provided to retain said doors in their locked positions. A bypass 41 is provided in each of the chutes to permit air to pass around doors 39 when desired and is operated by a valve 42. Extending from 20 tank 29 is an outlet valve 43 which is connected by a flexible tube 44 to working chamber 32 to supply the desired air pressure to said chamber, valve 43 being the means controlling the amount of air supplied to said chamber. Mounted upon platform 8 is a pump 45 adapted to pump water from the stream upon which the device is being used into the water chamber 31 and a valve 46 extending through partition 30 25 provides means for emptying the tank of water when desired. Valve 46 is operated by a rod 47 which extends upwardly and terminates above the top of the diving bell 18. In one of the corners of diving bell 18 30 is provided a chute 48 similar in all respects to chutes 34 and 35 excepting that the lower end is composed of glass or has glass windows therein and serves as a lookout chute from which the work being done on the 35 interior of the working chamber may be inspected without entering the same. Mounted on shaft 23 are winding drums 49 and 50 which are controlled by the usual controlling means and around which are adapted to 40 wind the hoisting cables 51 and 52. Cables 51 and 52 pass upwardly and over guide-wheels 53 and 54 and then downwardly centrally of chutes 34 and 35 and are provided to raise and lower the buckets 55 as here- 45 after explained. Extending outwardly from each end of diving bell 18 centrally thereof and a short distance below the top, are handles 56 and 57 to which are secured one end of controlling cables 58 and 59. Cable 55 50 extends upwardly and over an idler pulley 60 mounted in bearings 61 and 62 mounted on transverse cross piece 16 and then downwardly and winds around winding drum 64 suitably mounted on the plat- 55 form. Cable 59 extends upwardly and around an idler pulley 65 mounted in bearings 66 and 67 secured upon the cross piece 15 and then passes over idler pulley 60 and and is wound upon drum 64. Drum 64 is 60 controlled by the usual controlling means 65

and serves to raise or lower the diving bell when desired relatively to the barges 5. A sluice box 68 is mounted upon the top of platform 8 and is used in the usual manner. Mounted in working chamber 32 a short 70 distance from the bottom thereof are swinging shelves 69 mounted in suitable bearings secured to the walls of chamber 32 so that their free ends swing downward and their free ends are supported by chains 70 which 75 chains are connected at one end to said shelves and have their other ends secured upon a pin 71 loosely. Pins 71 are mounted in a revolving shaft 72 mounted in bearings 73 on the wall of chamber 32. One end of 80 shaft 72 has a handle 74 rigidly mounted thereon adapted to rotate said shaft when desired, and a lock 75 provides means for locking said handle against accidental movement. Mounted in chamber 31 at one 85 end thereof is a compressed air lifting jack 76 the lower end of which is connected to chamber 32 through an opening 77 in partition 30 so that the lower end of piston rod 78 may project downwardly into said chamber 90 95 32 or for a purpose hereafter explained. Chute 48 is provided with a plurality of steps or foot holds by means of which the operator may descend to the bottom or climb to the top. Secured upon the free end of each of cables 51 and 52 is a grappling hook comprising a bifurcated member 79 between the arms of which is mounted the hook or grappling member 80. Member 80 is mounted centrally of its length to swing 100 freely so that normally it will lie at right angles to member 79. A lanyard 81 has one end secured to one end of member 80 and its other end extends through the bifurcations of member 79 and then upwardly to a 105 suitable point of use so that when lanyard 81 is pulled upwardly member 80 will be drawn to lie parallel with member 79 and when lanyard 81 is released member 80 will 110 resume its normal position.

It will be understood that suitable means may be provided if necessary or desirable for illuminating the interior of chamber 32 and that an electric generator and storage battery or either of them may be added to 115 the equipment of our device when found necessary to the proper operation thereof. The buckets used in our machine are of a size and shape suitable to pass easily through the working chutes 34 and 35, but may be of any capacity desired. Each bucket is provided with an upwardly and inwardly extending handle 82 which terminates in a horizontal ring member 83 for engagement by the grappling hook when it 120 is desired to raise the buckets.

Valves 84 and 85 are provided in the walls of the work chutes to permit the operator to equalize the air pressure therein, the inner valve being used when the workers 130

are lowered down the chutes to enter the work chamber and the outer valve being used when removing material in the buckets. If desired a telephone system may be installed to permit communication with the working chamber while the device is in use.

In the operation of our device it will first be towed to the desired place of operation and anchored in any suitable manner. Water will then be pumped into the water chamber, drum 64 being first released, which forces the diving bell 18 downwardly until the bottom of the bell rests upon the bed of the stream, it being understood that, as the rails 19 are rigidly secured to said diving bell and travel therewith, as the diving bell is forced downwardly the projecting ends of said rails will be driven into the bed of the stream and anchor the device against movement. Water will continue to be pumped into the water chamber until sufficient has been pumped in to overcome the buoyancy of the compressed air to be pumped into chamber 32. Compressed air will then be pumped into chamber 32 until the water therein is expelled and will continue to be pumped therein to prevent water from reentering. It will be understood that the air tight doors 37 in the chutes will be closed before lowering the bell. The workmen are then lowered by means of cables 31 and 32 into chutes 34 and 35 doors 39 being opened until they are standing upon the bottom of the chutes. The cables are then withdrawn and the door 39 closed. The doors 37 are then opened and the workmen step out into the working chamber. Doors 37 are then closed and doors 39 opened and the buckets 55 are lowered to rest upon the bottom of the chutes. The cables are withdrawn, doors 39 are closed, and doors 37 opened when the workmen are free to fill the buckets with material. After the buckets are filled doors 37 are closed and doors 39 opened. The cable is lowered and the grappling member operated to engage ring 83 and hoist the buckets to the surface where they are emptied into the sluice box and again lowered. This operation is repeated as desired.

Extensions are provided for water chamber 31 and the chutes to be mounted upon the top thereof when it is desired to use the machine at a greater depth than one section will allow.

Having described our invention what we claim is:

1. In an underwater mining machine the combination with a float having vertically extending guideways, of a vertically movable diving bell carried thereby, a partition extending horizontally of said bell and forming two superposed chambers open at

their opposite ends, the upper chamber being a ballast chamber and the lower chamber being a work chamber; means to supply water into said ballast chamber to force said bell downwardly; an outlet for said water ballast; a pair of vertically extending chutes opening at the bottom into the work chamber and opening at the top to atmosphere above the top of said ballast chamber; closures for the openings at the bottom of said chutes; closures mounted within said chutes near the bottom thereof adapted to cut off the lower portions thereof from communication to atmosphere; guide rails carried by said bell engaging said guideways and having lower projecting ends whereby when said bell is lowered said projecting ends will be forced into the bed of the stream to anchor the device against movement.

2. In an underwater mining machine the combination with a float having vertically extending guideways, of a diving bell carried thereby; vertically extending guide rails carried by said bell and engaging said guideways to confine the same to a vertical movement only, the lower ends of said guide rails projecting below the bottom of said bell whereby when said bell is lowered said projecting ends will be forced into the bed of the stream to anchor the device against movement.

3. In an underwater mining machine the combination with a float having vertically extending guideways, of a vertically movable diving bell carried thereby and being divided intermediate its length into two superposed chambers, the upper chamber being the ballast chamber and the lower chamber being the work chamber; means to supply water into said ballast chamber; an outlet for said water ballast; a pair of vertically extending chutes opening at the bottom into said work chamber and at the top to atmosphere; closures for the openings in the lower ends of said chutes; means mounted within said chutes at the lower ends thereof adapted to cut off the lower portions thereof from communication to atmosphere; a plurality of swinging shelves mounted on the interior walls of said work chamber; means to normally hold said shelves positioned horizontally; means to release said last means; and guide rails mounted on said diving bell having lower projecting ends whereby when said bell is lowered said projecting ends will be forced into the bed of the stream.

In witness that we claim the foregoing we have hereunto subscribed our names this 11th day of February 1918.

FRANK L. GILMAN.
WILLIS M. BAUM.
